UNITED STATES PATENT OFFICE.

CHARLES CLYDE BOLEN, OF DANVILLE, VIRGINIA, ASSIGNOR TO DRAPER CORPORATION, OF HOPEDALE, MASSACHUSETTS, A CORPORATION OF MAINE.

TEMPORARY CLOTH-ROLL SUPPORT FOR LOOMS.

Application filed February 4, 1926. Serial No. 85,859.

This invention has for its object to provide a simple and efficient means for temporarily supporting the roll of cloth at the completion of the weaving operation and after 5 the cloth roll journals have been removed from the bearings in which they are supported during the weaving operation.

The object of the invention is to provide such means so that the completed roll of 10 cloth may be supported in a position where it will not be injured or soiled until it can be carried away from the weave roll.

When the weaving of a roll of cloth is completed, the roll is removed from the 15 loom by lifting the cloth roll journals out from the bearings at the front of the loom. The space around a loom is universally very much restricted and unless the roll is immediately carried away from the weave 20 room, which is usually not convenient, the operatives are likely to place the roll of cloth usually on one end wherever space is available, as, for example, at the side of the weave room and against the wall. This is 25 apt to soil and injure the cloth. Usually the services of two men are required to handle the roll and carry it away and something must be done with the roll until such services are available.

30 In the present invention suitable temporary supports are provided rigidly secured to the arch of the loom. The roll at the completion of the weaving operation is placed on these supports and is thus kept 35 free from danger of being soiled or injured, in a position out of the way and in a position from whence it may be taken at any time and carried from the weave room.

Since the invention is applicable to various 40 types of looms and since the general construction of the loom is not involved in the present invention, it is only necessary herein to illustrate and describe the devices of the invention itself in connection with the 45 loom arch to which these devices are rigidly secured.

In the drawings:

Fig. 1 is a view in front elevation of the 50 arch of a loom showing one of the harness frames and showing a preferred form of the

present invention, together with a roll of cloth indicated in dotted lines.

Fig. 2 is a view on a larger scale in side elevation and partially in cross section taken on the line 2—2 of Fig. 1.

55 A loom arch having the upright members 1 and the connecting cross bar 2 is shown, and supported therefrom the harness frame 3. The loom arch is shown as of channel shape presenting the front web 4, the rearwardly projecting top flange 5 and the rearwardly projecting bottom flange 6.

60 A plurality of temporary supporting brackets for the cloth roll are provided and, as herein illustrated, there are two such 65 brackets each of the same construction. Each bracket comprises a base 7 provided with a depending plate 8 adapted to seat against the front face of the web 4 of the loom arch and with a rearward projection 70 9 adapted to rest upon the top of the flange 5 of the loom arch. This base is provided with means by which the bracket is rigidly secured to the loom arch. For that purpose a bolt 10 is provided passing through suitable 75 apertures in the web 4 of the loom arch and the plate 8 of the base. A washer 11 and a nut 12 on the bolt clamp the parts rigidly together. The base 7 of the bracket 80 is provided with a forwardly projecting arm 13 presenting at the top a concave, substantially circular arcuate, seat 14 of sufficient size to receive the roll of cloth 15. The seat 14 is of substantial width and the arm is 85 strengthened by a mid-flange 16.

85 Each bracket may readily be, and is shown as, cast or formed in a single integral piece and is thus of comparatively inexpensive construction. The construction described also enables the brackets readily to be secured in a firm and rigid manner to existing looms without any change in the loom other than the boring of the necessary holes for the bolts 10 in the loom arch.

90 When the weaving operation has been completed, the operatives, after removing the cloth roll from the loom, simply lift it up and place it in the seats formed by the brackets where it is maintained out of the 95 way, without occupying any additional 100

floor space, and in a position where it is prevented from being soiled or injured.

Having thus described the invention, what is claimed as new, and desired to be secured by Letters Patent, is:—

In a loom, a plurality of temporary supporting brackets for the cloth roll, each comprising a base, means for rigidly securing

the base to the arch of the loom, and an arm projecting forwardly from the base and presenting at the top a concave seat to receive the cloth roll. 10

In testimony whereof, I have signed my name to this specification.

CHARLES CLYDE BOLEN.
